UNITED STATES PATENT OFFICE.

FREDERICK H. WILLCOX, OF CHICAGO, ILLINOIS, ASSIGNOR TO FREYN, BRASSERT & COMPANY, OF CHICAGO, ILLINOIS, A CORPORATION OF MAINE.

HOT-BLAST STOVE.

Application filed May 17, 1924. Serial No. 713,965.

To all whom it may concern:

Be it known that I, FREDERICK H. WILLCOX, a citizen of the United States, residing at Chicago, in the county of Cook and State 5 of Illinois, have invented certain new and useful Improvements in Hot-Blast Stoves, of which the following is a specification.

This invention relates to a new and improved hot blast stove construction and more 10 particularly to a construction of the inner and arch walls of the combustion chamber of such stoves and a method of keying the arch wall into the outer wall.

As at present generally constructed and 15 used, hot blast stoves comprise tall cylindrical chambers, lined with refractory brick. A vertical division wall is constructed, this wall being arched in cross section and springing from the lining wall and with the 20 lining wall forming a combustion chamber lenticular in cross section. The remainder of the stove is filled with brick checker-work through which the products of combustion pass and which are heated thereby.

The outer and arch walls of the combustion chamber, as now generally constructed, 25 comprise alternate key and straight bricks, the keys not being made of such shape as to permit their exclusive use. The fire clay 30 in which the bricks are laid, is gradually worked out from between the brick. This is due to a minute but continuous alternate expansion and contraction of the brick under the variable temperatures maintained 35 in the combustion chamber, these temperatures varying from one thousand to twenty-four hundred degrees as the combustion chamber is alternately used for combustion and for carrying off the air heated in the checkerwork. This expansion and contraction working on the fire clay mortar gradually loosens it and causes it to sift out. A further factor in this loosening of the brick 40 consists in the vibration which is set up in the combustion chamber by the ascending column of burning gases when burners are not correctly adjusted.

It has been found in actual practice that the straight bricks will gradually work out of the wall and after they have worked out, 50 adjacent key bricks will work out so that large areas of the combustion chamber wall will become insecure. Large numbers of brick fall out of the arch wall and eventually a hole is opened up into the checkers 55 whereupon the checkers also commence to fall out. On the shell side of the combustion chamber, the combustion chamber wall and lining walls similarly fall out which results in a hot burned spot on the 60 steel shell of the stove.

Another difficulty with present constructions lies in the fact that the inner or arch combustion chamber wall is not keyed into the outer combustion chamber or lining wall. 65 Consequently under the conditions of use which have been described, there is a tendency for the arch wall to separate from the outer wall. This tendency is further increased by the fact that the angle formed in 70 the checker chamber between the arch wall and outer wall is usually merely filled with broken brick which have little real stability.

It is an object of the present invention to provide a new and improved hot blast stove 75 construction in which the inner faces of the combustion chamber walls are formed of key brick throughout whereby each brick restrains inward movements of the adjacent brick.

It is a further object to provide construction in which the arch wall is formed of both key and straight bricks, the straight brick later being bonded into the inner fac- 80 ing of key brick.

It is also an object to provide a construction in which the arch wall is keyed into the outer wall at their points of junction.

It is an additional object to provide a construction in which the outer angle between 90 the arch and lining walls is filled with especially shaped key brick.

Other and further objects will appear as the description proceeds.

I have illustrated a preferred embodiment of my invention in the accompanying drawings, in which—

Figure 1 is an elevation of a stove partly broken away to show the interior construction;

Figure 2 is a fragmentary horizontal section showing the construction of certain courses of the brick in the combustion chamber walls;

Figure 3 is a section similar to Figure 2, but showing the arrangement of brick in other courses;

Figure 4 is a section on an enlarged scale taken on line 4—4 of Figure 3;

Figure 5 is a perspective view of the longer key brick;

Figure 6 is a perspective view of the shorter key brick; and

Figure 7 is a perspective view of the special key brick.

The stove as shown in Figure 1 comprises a metallic outer shell 11 and a brick lining 12 between which is placed a layer of refractory material 13. The burner opening 14 is placed at the lower end of the combustion chamber 15. The combustion chamber is separated from the checker chamber 16 by the arch wall 17. The checker chamber 16 may be filled with brick in any usual manner.

Referring now to Figures 2 and 3, the lining wall 12 of the stove is composed throughout the major portion of its circumference in Figure 2 and throughout its circumference in Figure 3 of usual types of straights and keys alternately placed. The thinner portion 18 adjacent the combustion chamber in Figure 3 is similarly formed of alternate keys and straights, the keys being shorter than those comprising the major portion of the wall.

The combustion chamber outer wall 19 as shown in Figure 3, is composed entirely of the long key bricks 20 shown in Figure 5. As shown in Figure 3, these keys 20 extend into the contour of the outer lining wall 12 of the stove. The arch wall 17, as shown in Figure 3, comprises the long key brick 20 upon the combustion chamber side and the straightbrick 21 laid as stretchers upon the checker chamber side.

Figure 2 shows the arrangement in other courses than those of the type shown in Figure 3. In this figure the outer combustion chamber wall 19 is composed of the short keys 22 of the type shown in Figure 3. These courses abut against the courses of the lining wall 12 which are formed throughout of alternate long keys and headers. The arch wall in the courses shown in Figure 2 comprises an inner facing of the short keys 22 and the outer portion 23 formed of straight brick laid as headers. The types of courses shown in Figures 2 and 3 may be

laid alternately as shown in vertical section in Figure 4.

As shown in Figure 3, the left end of the arch wall 17 extends into and across the outer wall 19. The right end of the arch wall 17 rests against the face of the outer wall 19 which latter extends across the arch wall. In the courses shown in Figure 2 the bonding is reversed the right end of the arch wall extending across the outer wall 75 and the left end of the outer wall across the arch wall. The angle formed in the checker chamber between the arch wall 17 and the outer lining wall 12 is filled by the special key bricks 24. These brick are made especially to fit the particular configuration of this location.

It is to be understood that the keys used alternately with straight brick in the outer lining wall of the stove, are not similar to 85 the keys 20 or 22. These lining wall keys are of usual standard construction and are not made in the proper proportions to be used without the alternation of a certain number of straights in order to form a compact wall for the usual size of stoves. The special keys 20 and 22, however, are especially designed for the arch into which they are built and form these walls without the necessity of the use of any straights. Thus 90 each one of the key brick in the combustion chamber wall is retained in place by the keying action of the adjacent bricks. Consequently no single brick can work out of the wall. My method of bonding the ends of 100 the arch wall into the outer wall, prevents separation of the arch and outer walls with consequent losses. This bonding is further strengthened by means of the solid keys 24 which fully and compactly fill the adjacent 105 angle.

I claim:

1. In a hot blast stove arch wall construction a plurality of courses, each course comprising a face portion formed of bricks segmental in plan whereby each brick is held against inward movement by engagement with the adjacent bricks and a backing portion formed of straight bricks.

2. In a hot blast stove arch wall construction a plurality of courses, each course comprising a face portion formed of bricks segmental in plan whereby each brick is held against inward movement by engagement with the adjacent bricks and a backing portion formed of straight bricks, the segmental bricks on certain courses being shorter than those on other courses, the straight brick behind the shorter segmental bricks being laid as headers and behind the other segmental bricks being laid as stretchers whereby the face and backing portions are bonded.

3. In a hot blast stove combustion chamber wall construction, outer and arch walls

each comprising a plurality of courses of bricks segmental in plan whereby each brick is held against inward movement by engagement with the adjacent bricks, the outer and arch walls being bonded by having alternate courses of the end each wall butting the adjacent wall and the intermediate courses extending through the depth

of the adjacent wall and special fill bricks solidly filling the angle in the checker chamber formed by the junction of the arch and outer walls. ¹⁰

Signed at Chicago, Illinois, this 14 day of May, 1924.

FREDERICK H. WILLCOX.

Certificate of Correction.

It is hereby certified that the assignee in Letters Patent No. 1,578,492, granted March 30, 1926, upon the application of Frederick H. Willcox, of Chicago, Illinois, for an improvement in "Hot-Blast Stoves," was erroneously described and specified as "Freyn, Brassert & Company," whereas said assignee should have been described and specified as *Freyn Engineering Company*, as shown by the records of assignments in this office; and that the said Letters Patent should be read with this correction therein that the same may conform to the record of the case in the Patent Office.

Signed and sealed this 18th day of May, A. D. 1926.

[SEAL.]

M. J. MOORE,
Acting Commissioner of Patents.
